SPINNING FRAMES
Ryohei Tsuzuki, 5 Yamayaki-cho, Handa-shi, Japan
Filed Jan. 14, 1960, Ser. No. 2,417
1 Claim. (Cl. 57—36)

This invention relates to spinning frames wherein a slubbing, roving, or sliver feeding part and/or a slubbing, roving, or sliver drafting part are or is enclosed in a chamber formed by a cover and cut off from outside air, in said chamber is maintained at a temperature and a humidity suitable for spinning.

In spinning factories, it is a common practice to effect air conditioning such that air throughout a large space is maintained at a temperature and humidity suitable for spinning. It is, therefore, impossible to locally maintain the air surrounding the roving or sliver feeding part and/or drafting part of the spinning frame at the temperature and humidity most suitable for spinning.

The above air conditioning to be effected throughout the large space requires not only installation and much expenses, but also results in adherence of flying and dust to sliver while it is spun, thus rendering production of yarn having improved quality difficult.

An object of my invention is to obviate the above disadvantages and spin an improved yarn in an extremely economical manner.

Other advantages are accomplished with my present invention as explained hereinafter and illustrated in the accompanying drawings, in which:

FIG. 1 is a vertical longitudinal sectional view of a spinning frame in accordance with my invention wherein a roving or sliver feeding part only is cut off from outside air;

FIGS. 2 and 3 are vertical longitudinal sectional views of spinning frames in accordance with my invention wherein the roving or sliver feeding part and drafting part are cut off from outside air;

FIG. 4 is a front view of the spinning frame shown in FIG. 2 partly in section; and

FIG. 5 shows mutual relations of temperature and humidity in the spinning frame in accordance with my invention and those in a conventional spinning frame.

Referring now to drawings, and especially to FIG. 1, numeral 11 designates a spinning frame as a whole, numeral 12 is a roller stand, numeral 13 shows a drafting part, and numeral 14 designates a cover adapted to form a chamber 15 enclosing the upper part of the drafting part 13. A creel 19 for supporting balling bobbins 18 is mounted in the chamber 15. Provision is made of a duct 16 communicated with a temperature and humidity adjusting room (not shown) and provided with a number of jet holes 17 opened inside the chamber 15. The jet holes 17 are adapted to feed air maintained at a temperature and a humidity most suitable for spinning into the chamber 15.

It is preferable to use the cover 14 made of transparent resin in order to facilitate the spinning operation.

It is most desired to add to the roving or sliver about 10% of water by the humid air fed into the chamber 15. The roving or sliver to which a suitable quantity of humidity has been given becomes about 8.5% in water content when drafted at the drafting part 13, so that the roving or sliver can be spun under the most suitable condition.

FIGS. 2 and 3 show other embodiments of this invention wherein the sliver feeding part and also the sliver drafting part are cut off from the outside air by means of the cover. In these embodiments, the chamber 15 is formed by a cover comprising a lower section 14₁ and an upper section 14₂. The lower cover section 14₁ encloses

2

therein the sliver drafting part 13 and the upper section 14₂ encloses therein the sliver feeding part consisting of balling bobbins 18 (FIG. 2) or cans 20 (FIG. 3). Provision is made of a number of apertures 23 at the bottom 5 of the lower cover section 14₁. These apertures 23 serve to guide the drafted yarn towards spools 24. The lower cover section 14₁ is provided at its front side with a door 22 adapted to be opened and closed. It is preferable that the upper cover section 14₂ is also provided with a suitable door which facilitates insertion and removal of the balling bobbins or the cans.

As mentioned above, this invention is intended to provide a spinning frame wherein the roving or sliver feeding part and/or drafting part are or is enclosed in a chamber 15 having a small volume such that the drafting process may be effected at a temperature and a humidity most suitable for spinning.

Thus, in accordance with the present invention the temperature and humidity existing in the roving or sliver feeding part and drafting part may locally be adjusted in a most efficient manner, so that the installation becomes simple and less expensive if compared with a conventional spinning frame for which temperature and humidity throughout a large spinning frame room are to be adjusted. Moreover, adherence of the flying and dust to sliver can never be occurred and fluffiness and break of yarn can be reduced, thereby obviating frequent clearing of the spinning frame and rendering the maintenance and management of the spinning frame simple and easy. Like this way, according to the present invention yarn of the highest grading may be obtained throughout all seasons.

FIG. 5 illustrates mutual relations of temperature and humidity in a spinning frame in accordance with my invention and those in a conventional spinning frame.

Table 1 shows results obtained by a spinning frame in accordance with my invention shown in FIG. 1. The yarn is No. 30s in count.

Table 3 shows frequency of break of yarn and amount of flying produced during spinning by a spinning frame in accordance with my invention and those produced during spinning by a conventional spinning frame.

Table 3

	Conventional spinning frame	Spinning frame according to my invention
Frequencies of break of yarn (during 1 hr. per 400 spindles)	19.63	11.26
Amount of flying (during 7.75 hrs. per 400 spindles), g.	27.8	8.29

In the above table, revolution of the spindles is 11,099 r.p.m., diameter of the rings is 50 mm., and the lift is 8 inch.

What I claim is:

A spinning frame comprising a base, roving feed means mounted on said base, roving drafting means mounted on said base and receiving rovings from said feed means, a cover mounted on said base and completely enclosing said feed means and drafting means therein closed off to the surrounding atmosphere, a duct within said cover having outlets therein, means for supplying air at a given temperature and humidity to said duct, spinning means mounted on said base exteriorly of, but adjacent said cover and said cover having apertures for guiding rovings from said drafting means to said spinning means.
